(57) **CLAIM**

The ornamental design for a bag for carrying articles, as shown and described.

DESCRIPTION

FIG. 1 is perspective view of the bag for carrying articles. FIG. 2 is a front elevational view of the bag for carrying articles.

FIG. 3 is a back elevational view of the bag for carrying articles.

FIG. 4 is a side elevational view of one side of the bag for carrying articles.

FIG. 5 is a side elevational view of the other side of the bag for carrying articles; and,

FIG. 6 is a top plan view of the bag for carrying articles. The bottom of the bag forms no part of the claimed design. The broken lines shown in the drawings illustrate portions of the article and form no part of the claimed design.
